BROODER

Leland G. Knapp, Chicago, Ill., assignor to
Montgomery Ward & Co., Incorporated, Chi-
cago, Ill., a corporation of Illinois

Application December 9, 1929. Serial No. 412,643

8 Claims. (Cl. 126—53)

The present invention has to do with brooders for chickens and the like, and is directed to the improvement of these devices on such lines as to simplify the same in the organization of their parts, and thereby effect material reduction in the manufacturing costs thereof.

To the accomplishment of these ends the invention contemplates a brooder, the heater or stove element of which is of such construction as to require but a minimum number of cast metal parts, thus reducing effectually the weight of the heater, and permitting an arrangement in the heater of base, fire-pot, body and top that will admit of the use of sheet metal and castings for producing the assembly.

The invention also aims to provide a sectional construction of the heater or stove element of the brooder by which the parts may be brought together or separated in an expeditious manner for replacement or repair, and without the necessity for the employment of skilled labor to effect the same.

A further object in view is the production of a heater or stove element for brooders wherein is included a novel arrangement of draft devices for maintaining and regulating the fire therein.

Other objects and advantages will appear as the nature of the improvements is better understood, the invention consisting substantially in the novel construction, combination and arrangement of parts hereinafter fully described, illustrated in the accompanying drawings, and finally pointed out in the appended claims.

The form of the invention made the subject of the present disclosure is a portrayal of a practical embodiment thereof, but it may be incorporated in other forms so that the delineation of the invention made the basis of this disclosure is to be taken in an illustrative and not a limiting sense.

In the drawings

Fig. 1 is a vertical transverse sectional view of a brooder constructed in accordance with the present invention;

Fig. 2 is a similar view of the top portion of the brooder on the line 2—2 of Fig. 1;

Fig. 3 is a view in side elevation of the top portion of the brooder, the cover being removed, the line of vision being towards the check draft of the brooder;

Fig. 4 is a detail sectional view on the line 4—4, Fig. 1;

Fig. 5 is a sectional plan view, broken away, illustrating the relation of the grate to the fire-

pot, and the manner of supporting the grate in the fire-pot;

Fig. 6 is a detail sectional view on the line 6—6, Fig. 1;

Fig. 7 is a detail elevation of the main air inlet 68 damper and its mounting;

Fig. 8 is a longitudinal sectional view of the check draft duct;

Fig. 9 is a top plan view thereof;

Fig. 10 is a side elevation of the check draft 65 duct;

Figs. 11, 12 and 13 are sectional views of the check draft duct on the lines 11—11; 12—12 and 13—13, Fig. 8;

Fig. 14 is a detail plan view of the closure for 70 the check draft duct.

Referring in detail to the accompanying drawings, the numeral 10 designates the base of the heater or stove element of the brooder. The latter is of the type in which solid fuel, such as 75 coal, is burned. The base 10 is annular in form and has an upwardly projecting flange 11 which fits within the lower end of a sheet metal body 12. This body is cylindrical in form, and its length is sufficient to provide an ash-pit 13 and 80 a combustion chamber 14. The lower end of the body 12 has a bottom plate 15, which constitutes a closure for that end of the body, and likewise forms the bottom of the ash-pit 13.

At an appropriate point above the bottom of 85 the body 12 there is formed in the sides of the latter an inwardly directed bead 16, thereby forming an annular supporting rib at the inner face of the body. This rib constitutes a seat for a bowl-shaped fire-pot 17. In assembling the 90 fire-pot 17 within the body 12 the fire-pot is introduced through the upper open end of the body 12 and moved into contact with the rib 16, and it is there fastened by means of a plurality of stove bolts 18, as shown. The fire-pot 17 has 95 a centrally disposed opening 19 which receives a circular gate 20. Surrounding the opening 19 is a depending annular flange 21, which flange is provided at diametrically opposite points with tapering sockets 22, and seated in said sockets 100 is a supporting bar 23 the ends of which are provided with tapering heads 24 that fit within the tapering sockets 22, and thereby hold the bar 23 in said sockets. The supporting bar 23 is perforated at its central portion and seated within 105 said perforated portion is a depending lug 25 by which the grate 20 is permitted to pivot on the bar 23. The lower end of the lug 25 has a trans- 110 verse opening therein for receiving a shaker bar 26, said bar being held within the lug 25 by a pin

27. By means of the shaker bar 26 the grate 20 may be oscillated on the supporting bar to shake the fire, the ashes gravitating from the grate being received by an ash-pan 28 located 5 in the ash-pit 13 and carried by an ash-pit door 29 which closes an opening 30 in the lower end of the body 12 and by which said opening is controlled.

With the tapering heads 24 loosely fitting in 10 the tapering sockets 22, the supporting bar 23 may be easily removed from the fire-pot 17 when occasion requires, thus enabling the grate 20 to be removed from the fire-pot and readily replaced therein.

15 At the upper end of the body 12 is located a dome-shaped top 31, which is cast to the desired form. This top has a depending flange 32 at its lower edge, and said flange fits within the upper end of the body 12 and is suitably secured thereto by stove bolts or equivalent fastenings. The central portion of the top 31 is perforated 20 to provide an opening 32a for passage of the products of combustion, said opening being surrounded by a flange 33 to which a smoke pipe 25 or chimney 34 may be connected.

The top 31 is also provided with a fuel feed 30 opening 35, preferably of oval shape to provide the desired capacity for the introduction of the fuel to the interior of the body 12, said opening 35 having a suitable closure 36 removably seated therein.

35 The dome top 31 is conical in form, and its lower edge has a depressed seat 37 extending circumferentially of the top. On the seat 37 is mounted a supporting ring 38 to which is connected the hover or canopy 39 of the brooder, which hover or canopy is conical in form and extends outwardly beyond the sides of the body 12 to the desired extent to form the brooding chamber 40 in which the chicks gather. The hover 39 is preferably formed of metal, and the same may be provided with a plurality of ribs 40 to reinforce or strengthen the same.

45 It is obvious that the lower edge of the hover 39 will be so located with reference to the base 10 as to provide the necessary clearance space between that edge and the floor on which the brooder is located for passage of the chicks into and out of the brooding space under the hover.

50 At one side of the ash-pit 13 is formed a main air feed or inlet opening 41 for passage of air to the fire-pot 17, thereby affording direct draft to the fire in the fire-pot 17, this opening being arranged at a point below the grate 20. The 55 opening 41 is surrounded by a casting 42 which has an opening 43 that registers with the opening 41. The casting 42 is held in position on the body 12 with respect to the opening 41 by a plurality of stove bolts or equivalent fastenings, 60 and said casting has formed at opposite sides of the opening 43 a pair of curved lugs 44 which constitute bearings for outwardly extending hinge lugs 45 carried by an air inlet damper 46. This damper controls the openings 43 and 41, 65 and when seated in closed relation thereto the passage of air into the ash-pit is prevented.

The damper 46 is thermostatically controlled. This is accomplished by the usual form of thermostat now commonly employed in brooders of 70 this type, the same including a supporting arm 47 which is removably connected to the casting 42, the arm 47 having a depending screw 48 on which is mounted a thumb nut 49 between which and the outer end of the arm 47 is adjustably 75 mounted an actuating bar 50. The bar 50 may

be adjusted on the screw 48 by the nut 49 towards and away from the bar 47, thermostatic wafers 51 also being interposed between the actuating bar 50 and the supporting bar 47. The action of this type of thermostat is well known, the expansion of the wafers, when subjected to the heat under the hover 39, serving to move the actuating bar 50 away from the bar 47, said bar 50 moving towards the bar 47 when the wafers 51 have contracted on reduction of the temperature beneath the hover.

80 Adjacent the upper end of the body 12 the latter is provided with a bleeder or check draft opening 52. This is positioned at such point in the body 12 as to be beneath the hover 13 and in communication with the brooding chamber beneath the hover when the latter is supported by the ring 38 from the seat 37. At the exterior of the body 12 the check draft opening 52 is surrounded by a casting 53, said casting being secured in position about the opening 52 by stove bolts or other suitable fastening. As clearly 85 shown in Fig. 1, the casting 53 is substantially triangular in cross-section, and the same is formed with an opening 54 which registers with the opening 52 in the body 12. The openings 54 and 52 are controlled by a check draft damper 55 suitably hinged, as at 56, to the lower portion of the casting 53, and cooperating with the latter to close the opening 54, when such is required. At 90 the outer side of the check draft damper 55 is located an attaching lug 57, and at the inner side thereof is arranged a contact finger 58 of such length as to engage with the upper edge of the openings 52 and 54, if such be required, to limit 95 the outward throw of the check draft damper 55. A connecting rod 59 is attached to the lug 57 at the upper end of said rod, the lower end being suitably connected to the actuating bar 50 of the 100 thermostatic controlling device. A similar connecting rod 60 extends from the lug 57 to an attaching finger 61 on the air inlet damper 46. Thus it will be seen that the actuation of the bar 50 by the expansion and contraction of the wafers 51 will cause the air inlet damper 46 and the 105 check draft damper 55 to be operated in unison, one moving to closing position, and the other to opening position, and vice versa, according to the movement of the actuating bar 50 under the action of the wafers 51.

110 It is the object of the air entering the check draft opening 52 to check the fire in the fire-pot 17 by bleeding hot air into the flue draft, and thus enable the fire to be regulated in accordance with the temperature that is required under the 115 hover 39.

120 To direct the incoming air which enters the opening 52 for the purpose stated a check draft duct 62 is employed. This duct is in the form of a channel casting, the same being illustrated in 125 detail in Figs. 8 to 13, inclusive. It includes an inclined body portion 63, which conforms to the inclination or slope of the dome-shaped top 31. At the upper end of the body portion 63 is located a perforated head 64, which extends at an 130 angle to the body portion 63, and occupies a substantially horizontal position beneath the central portion of the top 31 so that the perforation or opening 65 of said head 64 is in substantial registry with the opening 32a through which the 135 products of combustion pass.

140 At the lower end of the body portion 63 is a vertically disposed foot 66, which extends at an angle to the body 63 so as to lie substantially 145 parallel with the adjacent vertical wall of the 150

body 12. This foot 66 has an attaching flange 67 by which it is secured to the inner face of the body 12 in surrounding relation to the check draft opening 52. The stove bolts which hold the casting 53 in position about the opening 52 may be conveniently employed for fastening the foot 67 of the check draft duct in position about the opening 52.

As clearly seen in Figs. 11, 12 and 13 the channel construction of the check draft duct imparts dished formation to the same transversely thereof, thereby providing lateral flanges at the side edges of the duct, which flanges extend from the lower end of the duct to the upper end thereof. These flanges bear against the inner side walls of the body 12, the inclined portion of the top 31, and the central upper portion of the latter. The side flanges fit between spaced ribs 68 which are formed on the inner face of the dome-shaped top 31, so that the check draft duct 62 in cooperation with the top 31 and the inner face of the body 12 forms a flue for passage of the air from the opening 52 to the opening 32a of the top 31. Due to the position of the side flanges of the duct between the ribs 68 this flue is sealed against draft, except as the draft is exerted at the interior thereof by reason of its communication with the smoke pipe or chimney 34, and by reason of the substantial length of the duct at the side and above the combustion area, the extraneous air bled through the duct into the flue is highly heated and serves to minimize the flue draft upon the fuel rather than apply a blanket of cold air, thus rendering the control of combustion much more sensitive and gradual, enabling the variation of temperature to be maintained within small limits.

The check draft duct 62 is held in contact with the top 31 by a fastening bolt 69, or its equivalent.

For graduating the size of the opening of perforation 65 of the check draft duct a closure 70 is associated therewith. This is provided with a pair of hinge lugs 71 which are connected to a corresponding lug 72 formed on the head 64, the closure 70 being of sufficient dimension to cover the opening 65 when closed thereagainst, if such should be necessary at any time. Normally, the closure 70 is in spaced relation to the head 64 so as to uncover the opening 65 and thereby establish communication through said opening to the opening 32a to permit passage of the products of combustion from the fire. The closure 70 has a slot 73 formed therein at a point opposite to the hinge lugs 71, said slot 73 receiving the head of a carriage bolt 74 which passes upwardly through the dome-shaped top 31 to the exterior thereof where its threaded end is provided with an adjustment nut 75 to permit adjustment of the bolt 74 in such manner as to swing the closure 70 either towards or away from the opening 65 in the head 64 of the check draft duct.

In the use of the herein-described brooder, fire is built in the fire-pot 17, coal being used preferably as the fuel. The hoover 39 is positioned on the stove or heater element by placing the supporting ring thereof on the seat 37. This ring, therefore, provides a central opening at the top of the hoover 39 through which the dome-shaped top 31 projects. This exposes the fuel opening 35 and its cover 36 so that the same is at the outside of the brooder and conveniently accessible for the introduction of fuel to the body 12 of the stove element when it is desired to re-fuel the same. Thus, there is no necessity for raising the hoover 39 when the fire requires re-fueling, and

the same remains in position on the stove element, thereby avoiding change in the temperature conditions under the hoover 39 and the brooding chamber which is therebeneath. Before the temperature conditions in the brooding chamber have risen to the degree necessary to affect the thermostatic wafers 51, to cause the same to expand, the positions of the main draft damper 46 and the check-draft damper 55 are as shown in Fig. 1. As there illustrated, the former is open, and the latter is closed. This affords a direct draft of air through the air inlets 41 and 43 to the ash-pit, and the same rises through the fire-pot and the fuel therein to the combustion chamber, and passes on to the smoke pipe or chimney 34. It will be understood, of course, that communication is established between the combustion chamber 14 and the smoke pipe or chimney 34 by a proper adjustment of the closure 70 of the opening 65. Dependent upon the degree of draft which it is desired to normally maintain in the fire-pot and combustion chamber, the closure 70 is adjusted in relation to the opening 65. Such adjustment is effected by proper manipulation of the nut 75 carried by the adjusting screw 74 to which the closure 70 is connected. This closure may be positioned more or less towards or from the opening 65, so that products of combustion readily may pass from the combustion chamber 14 to the smoke pipe or chimney 34. But this adjustment may be changed from time to time to meet changing atmospheric conditions. It is obvious, therefore, that the construction just described provides a simple and efficient expedient for regulating the draft in the stove element. As the temperature of the air in the brooding chamber beneath the hoover 39 rises the same will affect the thermostatic wafers 51 to cause the same to expand. As before stated, these wafers are of a well-known type, being filled with ether or other volatile liquid capable of ready expansion and contraction under changing heat conditions. As the wafers expand the actuating bar 50 is moved away from the supporting bar 47, thereby exerting a pull on the connecting rod 59. This moves the check-draft damper 55 into open position with respect to the check-draft opening 52, and in such movement of the check-draft damper 55 the connecting rod 60 is moved downwardly, and thereby acts to move the main damper 46 to closed position. It will be understood that the relative movement of the dampers 46 and 55 is determined by the adjustment of the thermostatic controlling device, such adjustment providing for such relative positioning of the dampers that the main draft openings 41 and 43, and the check-draft openings 52 and 54 may be partially open at the same time, or the main draft openings may be closed and the check draft openings open, or vice versa, as conditions of operation of the brooder may require, all of these movements being under the control of the thermostatic device which responds to the temperature changes in the air under the hoover 39. By such automatic movement of the dampers 46 and 55 the fire is controlled, and even temperature maintained in the air beneath the hoover 39. That temperature is determined by the age of the chicks, the thermostatic device being set for such temperature by manipulation of the nut 49 on the screw 48 to vary the action of the wafers 51 in the movement of the actuating bar 50. It will be understood also that when the temperature falls the wafers 51 contract, and at such

time the preponderant weight of the check-draft damper 55 will cause the latter to move to its closing position relative to the check draft opening 52, and thereby move the actuating bar 50 towards the supporting bar 47.

Brooders of the character herein described are usually operated under conditions which require fuelling and shaking of the fire approximately only once in every twelve hours. Thus, after 10 the stove element has been given attention in this respect it is unnecessary to exercise further care in the maintenance of the fire, the latter being automatically controlled by the thermostatic device, and even temperature maintained 15 thereby under the hover 39.

I claim:

1. In a brooder, a stove element including a body having a fire-pot and a combustion chamber and a flue, said body being provided with 20 a draft controlling damper below the fire-pot and with a check-draft opening at a point above the fire-pot, the damper and check coupled to open and close thermostatically in unison, and also provided with a flue opening for escape of the 25 products of combustion, independent dampers for the check draft opening and for the flue opening, a channeled member arranged at the inner side of the body and communicating with said check-draft opening and with the flue beyond 30 the said flue opening, said channeled member cooperating with the inner walls of the body to constitute a check-draft duct between the check-draft opening and the flue, and means for connecting said channeled member to the body.

35 2. In a brooder, a stove element including a body having a fire-pot and a combustion chamber and a flue, said body being provided with a draft controlling damper below the fire-pot and with a check-draft opening at a point above the 40 fire-pot the damper and check coupled to open and close thermostatically in unison, and also provided with a flue opening for escape of the 45 products of combustion, independent dampers for the check draft opening and for the flue opening, a channeled member arranged at the inner side of the body and provided with head and foot portions, the head portion being in communication with the flue beyond the flue opening and the foot portion in communication with the 50 check-draft opening, said channeled member cooperating with the inner walls of the body to constitute a check-draft duct between the check-draft opening and the flue, and means for connecting said channeled member to the body.

55 3. In a brooder, a stove element including a body having a fire-pot and a combustion chamber and a flue, said body being provided with a draft controlling damper below the fire-pot and with a check-draft opening at a point above the 60 fire-pot, the damper and check coupled to open and close thermostatically in unison, and also provided with a flue opening for escape of the 65 products of combustion, independent dampers for the check draft opening and for the flue opening, a channeled member arranged at the inner side of the body and provided with a head and foot portions, the head portion being in communication with the flue beyond the flue opening and the foot portion in communication with the 70 check-draft member, said channeled member cooperating with the inner walls of the body to constitute a check-draft duct between the check draft-opening and the flue, means for connecting said channeled member to the body, the 75 head portion of said channeled member carry-

ing the flue opening to afford communication between the combustion chamber and said flue, and adjustable means for controlling the area of the flue opening in said head portion.

4. In a brooder, a stove element including a body having a fire-pot and a combustion chamber and a flue, said body being provided with a draft controlling damper below the fire-pot and with a check-draft opening at a point above the fire-pot, the damper and check coupled to open and close thermostatically in unison, and also provided with a flue opening for escape of the products of combustion, independent dampers for the check draft opening and for the flue opening, a channeled member arranged at the inner side of the body and provided with a head and foot portions, the head portion being in communication with the flue beyond the flue opening and the foot portion in communication with the check-draft opening, said channeled member cooperating with the inner walls of the body to constitute a check-draft duct between the check draft opening and the flue, means for connecting said channeled member to the body, the head portion of said channeled member carrying the flue opening to afford communication between the combustion chamber and said flue, a closure hingedly connected to said member and cooperating with the opening in said head portion for controlling the area thereof, and means for adjusting said closure in relation to said opening to vary the area of the opening.

5. In a brooder, a stove element including a body having a fire-pot and a combustion chamber and a flue, said body being provided with a draft controlling damper below the fire-pot and with a check- draft opening at a point above the fire-pot, the damper and check coupled to open and close thermostatically in unison, and also provided with a flue opening for escape of the products of combustion, independent dampers for the check draft opening and for the flue opening, a channeled member arranged at the inner side of the body and provided with head and foot portions, the head portion being in communication with the flue beyond the flue opening and the foot portion in communication with the check-draft opening, said channeled member cooperating with the inner walls of the body to constitute a check-draft duct between the check-draft opening and the flue, the inner walls of the body having spaced ribs between which the sides of said channel member are fitted, whereby to seal the check-draft duct against draft, means for connecting said channeled member to the body, the head portion of said channeled member carrying the flue opening to afford communication between the combustion chamber and said flue opening, and adjustable means for controlling the area of the opening in said head portion.

6. In a brooder, a stove element including a body having a fire-pot and a combustion chamber and a flue, said body being provided with a draft controlling damper below the fire-pot and with a check-draft opening at a point above the fire-pot, the damper and check coupled to open and close thermostatically in unison, a dome-shaped top surmounting the body and provided with a flue opening for escape of the products of combustion, independent dampers for the check draft opening and for the flue opening, a channeled member arranged at the inner side of the body and including head and foot portions arranged at an angle to the body portion of said

member, the head portion being disposed substantially horizontally across said top and in communication with the flue opening, the body portion of said member conforming to the contour of said top, and the foot portion being vertically disposed and conforming to the vertical wall of the body of the stove element from a point substantially midway of the height of the combustion chamber, said channeled member cooperating with the body of the stove element to constitute a check-draft duct between the check-draft opening and the flue beyond the flue opening, and means for connecting said channeled member to the body.

7. In a brooder, a stove element including a body having a fire-pot and a combustion chamber and a flue, said body being provided with a draft controlling damper below the fire-pot and with a check-draft opening at a point above the fire-pot, a damper and check coupled to open and close thermostatically in unison, a dome-shaped top surmounting the body and provided with a flue opening for escape of the products of combustion, independent dampers for the check draft opening and for the flue opening, a channeled member arranged at the inner side of the body and including head and foot portions arranged at an angle to the body portion of said member, the head portion being disposed substantially horizontally across said top and in communication with the flue opening, the body portion of said member conforming to the contour of said top, and the foot portion being vertically disposed and conforming to the vertical wall of the stove element from a point substantially midway of the height of the combustion chamber, said channeled member cooperating with the body of the stove element to constitute a check draft duct between the check-draft opening and the flue beyond the flue opening, means for connecting said channeled member to the body, the head portion of said channeled member carrying the flue opening to afford communication between the combustion chamber and said flue opening, a closure hingedly connected to said member and cooperating with the opening in said head portion for controlling the area thereof, and means for adjusting said closure in relation to said opening to vary the area of the opening.
